(57) **CLAIM**

The ornamental design for a vegetable steamer, as shown and described.

DESCRIPTION

FIG. 1 is a perspective view of a vegetable steamer showing my new design.

FIG. 2 is a front elevation view thereof; the rear elevation view is identical thereto.

FIG. 3 is a side elevation view thereof; the opposing side elevation view is identical thereto.

FIG. 4 is a top plan view thereof; and,

FIG. 5 is a bottom plan view thereof.

The broken lines in the figures form no part of the claimed design.
